UNITED STATES PATENT OFFICE.

JOHN J. DIEHL, OF BOSTON, MASSACHUSETTS.

RECORDING-MACHINE.

1,323,846.

Specification of Letters Patent.

Patented Dec. 2, 1919.

Application filed March 19, 1917. Serial No. 155,649.

To all whom it may concern:

Be it known that I, JOHN J. DIEHL, a citizen of the United States, and resident of Boston, county of Suffolk, and Commonwealth of Massachusetts, have invented an Improvement in Recording-Machines, of which the following description, in connection with the accompanying drawings, is a specification, like characters on the drawings representing like parts.

This invention relates to record making machines and particularly to one applicable for use by a person having a periodical series of dealings with a number of clients or customers. An example of such a person is a banker, and the machine which I have chosen for illustration herein as exemplifying my invention is designed for use in administering one of the so-called "Christmas clubs" wherein a number of customers of the bank make periodical deposits which are repaid at a stated time before Christmas. For convenience I shall describe my invention by reference particularly to such use, since to do so will permit of a concreteness which will render the invention more readily apprehended.

My invention will best be understood by reference to the following description of the illustrated embodiment thereof shown in the accompanying drawings, wherein:

Figure 1 is a plan view of a machine embodying my invention with parts broken away;

Fig. 2 is a view of a portion of the front face or obverse of a depositor's receipt card or book adapted to be used with the machine of Fig. 1;

Fig. 3 is a view of the reverse thereof;

Fig. 4 is a view showing a record slip made by the machine;

Fig. 5 is a plan of the machine with the covers removed and parts broken away;

Fig. 6 is a section on line 6-6 of Fig. 5; and

Figs. 7, 8 and 9 are sections on the like numbered lines of Fig. 6.

To simplify the description of the mechanical construction of the machine shown, I will first describe the particular results obtained from its use. The machine is adapted to be used by the banker in connection with depositors' pass-books or cards 3, shown in Figs. 2 and 3. When a payment is made by a depositor it is received for on his pass-book and a record is made for use

by the banker corresponding to a journal entry from which his ledger account may be posted. The present machine provides means whereby the received record and the journal entry record may be made with minimum labor and without possibility of mistake.

In the embodiment of the invention chosen for illustration, the card or deposit book 3 has on one side thereof (Fig. 2) a tabulation of the dates when payments are due, blanks 5 being provided for marking or printing upon the card a record of the date on which the various payments were received. A portion of the card also has a surface formed in such manner as to permit an identifying imprint of the card to be made therefrom. In the form here shown, the card has attached to one end thereof, conveniently on the side opposite the tabulation referred to, a plate 7 having raised characters thereon. In Fig. 3 the characters "100-1247" are shown on the card 3, "100" indicating that the holder's weekly deposit is \$1.00, "1247" being a designation of the particular account which he has with the bank. The machine which I am about to describe not only stamps the receiving date in one of the blanks 5, but forms a record for the banker which may be like that shown in Fig. 4, consisting of a slip of paper, conveniently a length of paper strip or tape. In Fig. 4 the numeral 23 indicates that the payment received for was the twenty-third payment, in other words, that the twenty-third blank space 5 was stamped with a receiving date. The legend "6-4-17", of course, is a record of the date on which the payment was made, being June 4, 1917, and the legend "100-1247" is an identification of the particular account to which the payment is to be credited and the particular pass-book or card in which a receipting entry was made.

Having thus described the results which are obtained by the use of my machine, I can more readily proceed with a description of the mechanical construction here shown for purposes of illustration. In exterior appearance the machine takes the form of a suitable box or casing, as best illustrated by Figs. 1 and 9, having suitable operating handles projecting therefrom, which handles will be described hereafter in their logical place. The box 9 has a cover 11 cut away as shown at 12 to facilitate

tate the positioning of the depositor's pass-book 3, which, as shown in Figs. 1 and 9, is inserted between a bottom plate 13 and a top plate 15, which top plate has flanges 17 engaging two adjacent edges of the book to position the same. The plate 13 is cut away as shown in Fig. 9 at 19, so that the blanks 5 of the positioned card are accessible from the interior of the box. The 10 plates are also apertured as shown at the left in Fig. 1, so that the printing plate 7 on the pass-book card 3 projects out into the apertures beyond the main portions of the plates, as clearly seen in Fig. 6. The 15 records for the banker's use are herein shown as made upon a strip of paper tape 21, best shown in Fig. 6, led from a supply roll 23 within the box over the top plate 15 and over suitable guides as shown, if 20 necessary, and through a pair of feed rolls 25 and thence through opening 27 to the exterior of the box. Herein the records are adapted to be made upon the tape 21 by ribbon printing, an inking ribbon 29 25 extending from roll 31 over the top plate 15 in cooperation with the tape 21 to a feeding roll 33. The tape 21 and ribbon 29 are shielded by the plate 15 from the operation thereon of any mechanism within the box, 30 except at the left where the plate is apertured as already described to expose the printing plate 7 of the card 3. A platen or impression surface 35 may be carried by the cover of the box opposite this opening.

I will next describe the mechanism by which records are concomitantly made on the card 3 positioned as described, and upon the tape 21. The printing mechanism is 40 carried by a suitable frame (Fig. 6) comprising end pieces 37 and 39 connected by a rod 41. The end pieces are mounted to slide on vertical posts 43 (Figs. 6 and 9), and the frame is normally held in the depressed position shown in those figures by means of springs 45, encircling the posts and held by nuts 47 in position to bear against the end pieces 37 and 39. Mounted to slide along the connecting rod 41 is a 45 traveling block 49 which carries marking means adapted (see Fig. 9) to mark upon the card 3 through the opening 19 in the plate 13. In the present embodiment of the invention the marking means 51 carried by the block 49 is a self-inking dating stamp in itself of well known form and having shiftable type adapted when pressure is put upon the stamp to be swung from engagement with an inking pad into position 50 to print upon the surface against which the stamp is pressed. The position of the block 49 along the connecting rod 41 determines in what one of the blanks 5 the stamp will mark. The block 49 may be 55 longitudinally adjusted (see Figs. 5 and 9)

by means of a handle 53 extending to the exterior of the box and hinged to block 49, as shown in Fig. 9, so that it may swing vertically. Up and down movement of the block and frame will therefore not be impeded by the handle. On the handle 53 is an index 55 adapted (see Fig. 1) to co-operate with a scale 57. The fact that the card 3 is positioned in the machine by the fixed flanges 17, renders it possible accurately to mark any desired one of the blanks 5.

Also carried by the frame, herein by the end piece 39, are suitable impression means co-operating with the platen 35. I have 80 herein shown a presser device 59 so arranged as to press the portion of the card 3 bearing the type plate 7 against the inking ribbon, paper strip and cooperating platen. Adjacent this presser may be mounted the 85 removable type 61 herein designed to record the date. It will be understood that the type 61 may be changed each day when the dating stamp 51 is adjusted.

An important feature of my invention is 90 means which I have provided whereby a record is made of the particular payment for which a receiving entry is made on the depositor's card. For this purpose I utilize suitable shiftable type members carried by 95 end piece 39 and co-operating with platen 35. I have here shown these devices as consisting of two type-carrying wheels 63 and 65. Assuming that there are fifty weekly payments to be made, each of these 100 wheels may carry twenty-five numbers and a suitable blank, use of two wheels permitting sufficient numbers to be provided for without unduly increasing the size of the wheels. Means are provided whereby the 105 movement of the block 49 and of the dating stamp carried thereby will be communicated to the type wheels 63 and 65 in such manner that they are set so as to print upon the paper strip 21 a record of the particular 110 position in which the stamp 51 was when the machine was operated or, in other words, what blank 5 of the card in the machine was marked. One suitable mechanism is here 115 shown for effecting this. I have illustrated 115 the type wheel 63 as fast on a shaft 67 journaled in the end piece 39, and the wheel 65 as carried by a sleeve 69 loosely surrounding the shaft 67. Pinions 71 and 73 are carried by sleeve and shaft respectively, and 120 these pinions are geared respectively to pinions on longitudinal shafts 75 and 77 having journal bearings in the two end members 37 and 39. It is obvious that rotation of the shaft 75 will, through the gear 71, 125 turn the wheel 63 without affecting the wheel 65, and similarly rotation of the shaft 77 will turn wheel 65 independently of the wheel 63.

The longitudinal movement of the block 130

49 carrying the dating stamp 51 is arranged to rotate in proper degree one of the shafts 75 and 77. For this purpose each of the shafts is provided on a part of its length 5 with a spiral groove, as clearly seen in Figs. 5 and 6. As best shown in Fig. 9, the block 49 has two nut-like portions 79 and 81 having interior pins or projections entering the grooves of shafts 75 and 77 respectively. 10 The spirally grooved part of one shaft is adjacent the ungrooved part of the other, so that as the block 49 (Fig. 5) is moved along the rod 41 and consequently along the two shafts, one of the nut-like portions will act 15 to rotate its corresponding shaft, while the other nut-like portion will be idle, not being in engagement with the spiral on its shaft. In order to insure that one shaft shall not move while the other is being operated, 20 the shafts where not spirally grooved may have straight grooves 83 therein, as seen in Fig. 6. Thus when the interior projection of the nut rides out of coöperation with the spiral groove on the shaft, it will 25 enter the straight groove and the nut will be locked to the shaft by a feather and groove connection and hold the shaft against rotation while the companion nut-like member is freed from its locking engagement 30 with the other shaft and may rotate the same by action on the spiral groove. It will thus be seen that when, as seen in Fig. 1, the handle 53 is adjusted with respect to the scale 57, the dating stamp 51 is shifted so as to make 35 the recording entry in the proper blank 5 (Fig. 2) of the card 3, and the type wheels are also shifted so as to be in position to record the number of that blank on the paper tape, thus making the record shown 40 in Fig. 4, wherein the numeral 23 is stamped by the type wheel 65 in the position shown in Fig. 5, the date "6-4-17" is stamped by the removable type 61, and the identifying record "100-1247" is made by 45 the plate 7 (Fig. 6) which is pressed by presser 59 into coöperation with paper 21, inking ribbon 29 and platen 35.

To cause the two record surfaces to be marked by the types described, the entire 50 frame comprising end pieces 37 and 39 and connecting rod 41, together with the mechanism carried thereby, may be reciprocated along the guide rods 43 against the force of springs 45. For this purpose rock shafts 87 and 89 are provided having levers 91 and 93 conveniently provided with anti-friction rollers, as shown, which are adapted to engage beneath the connecting bar 41. The shaft 87 may be rocked by means of the 55 hand crank 95 exterior to the box (Fig. 9) and equivalent motion is communicated to shaft 89 by means of the parallel crank arms 97 and 99 connected by the link 101. A suitable spring 103 (Figs. 6 and 9) is 60 provided to hold the levers 91 and 93 nor-

mally in engagement with the rod 41. The springs 45 which depress the frame will normally bring the end of the crank 95 to the position shown in Figs. 6 and 9. It will be understood that if the crank 95 is rocked 70 to the right, viewing Fig. 6, that the whole frame will slide on the posts 43, that the dating stamp 51 will be pressed against the card 3 to make a mark thereon, that the type presented by the wheels 63 and 65, and 75 the type 61 will press the paper strip 21 and its coöoperating inking ribbon 29 against the platen 35, and that the presser 59 will press the plate 7 carried by the card 3 also against the platen to make a mark upon the paper strip. It may be here noticed that in the embodiment of the invention shown the paper is placed in front of the inking ribbon as regards the type. This reversal of the customary practice of ribbon printing 80 as found in typewriters and like instruments, is due to a desire to have the type of the plate 7 in its ordinary legible position, as shown in Fig. 3, and not reversed as would be necessary if an unreversed mark were 90 to be made by the plate through a ribbon and on a paper beneath that ribbon.

In the present embodiment of my invention the reciprocation of the frame described also acts to feed forward the paper strip 95 and the inking ribbon so as to bring fresh portions thereof in position for the next recording operation, and also provides for cutting off a length of the paper so that the records of the various receipts recorded by 100 the machine may be preserved in the form of slips, as shown in Fig. 4, from which bookkeepers may post the bank's ledgers.

I shall first describe the means by which the paper and the ribbon are fed. Referring to Figs. 5, 6 and 8, I have here shown a sprocket wheel 104 on the journal of one of the feed rolls 25 connected by a sprocket chain 105 with a sprocket wheel 107 loosely mounted on rock shaft 89. Secured to the 105 hub of the sprocket 107 is a ratchet wheel 109. The crank arm 99 already referred to may carry a pawl 111 adapted to coöperate with this ratchet. Referring to Fig. 6, it will be seen that when the frame is lifted 110 to print, the arm 99 swinging to the left will draw the pawl 111 idly across the ratchet teeth. When the frame descends the pawl will drive the ratchet and the sprocket 107 attached thereto, and through the sprocket 115 chain 105 the feed roll 25. Thus the paper is at rest while printing is being done and is fed forward between printing operations.

To feed the ribbon the journal of the roll 33 on which it is wound is provided with a 120 ratchet wheel 112, and a pawl 113 is provided upon rod 115 suspended at one end by the link 117 from the journal of the roll and at its other end having a slot guided on a pin 119 in the frame of the box (see Fig. 5). 125

65

The rod 115 is normally drawn to the right, viewing Fig. 6, by the spring 121 and has an extending arm 123 adapted to coöperate with a notch 125 in the connecting rod 101 somewhat in the manner of a pawl with a ratchet rack. It will be understood from an inspection of Fig. 6 that when the connecting rod 101 is moving to the right, the rod 115 will be drawn to the right by spring 121 as far as the pin and slot connection 119 will permit. In such movement the pawl 113 is idle. When the connecting rod 101 returns to the left the notch will hold the arm 123 and the rod 115 will be driven to the position shown in Fig. 6, and in this movement the pawl 113 will engage the ratchet teeth carried by roll 33 and impart feeding movement to the ribbon. As in the case of the paper strip 21, the feeding movement of the ribbon is during the return movement of the frame after printing has been effected.

I shall next describe the mechanism here illustrated for severing the portions of the paper strip 21 which have been printed upon, and in doing so shall refer principally to Figs. 6 and 7. The paper strip adjacent the opening 27 which leads to the exterior of the box is guided over a support 127 which holds it in operative relation to a fixed shear blade 129. The coöperating shear blade 131 extends beneath the opening 27 and is pivoted at 133 to the end of the box. A spring 135 surrounding the pivot pin and a spring 137 at the opposite end of the shear surrounding a pin which works in a slot 139 therein hold the blade to its work so that it will make a clean cut in coöperation with the fixed blade 129. The movable blade 131 is normally separated from blade 129 being drawn down against stop 141 by a spring 143. To give cutting movement to the blade, a link 145 is pivoted thereto which link has a shoulder which is held in engagement with an extension 147 of the end piece 39 by means of a spring 149. It will be understood from an inspection of Fig. 6 that when the frame rises and while the paper strip is stationary, the movable blade 131 will be actuated to sever the length of paper which projects through the opening 27. Since the travel of the frame is in the present instance greater than the desired movement of the shear blade, means are provided for throwing the link 145 out of engagement with the extension 147. In the present example a diagonally positioned member 151 is secured to the end of the box and is adapted to coöperate with a pin 153 on the link 145. When the link has lifted the blade 131 a sufficient distance to sever the paper, the pin 153 will ride along the diagonally disposed face of member 151, thus swinging the link 145 against the force of spring 149 and out of engagement with the extension 147. To

prevent the strip from curling over the face of blade 129 and to guide it for feeding through the opening 27, a yielding keeper 155 may be provided opposing the blade 131. Herein I have shown the keeper as a slotted bar having a lower edge normally presented substantially flush with the lower edge of the blade 129. The bar is mounted on screws 157 passing through the vertical slots therein and may thus yield upwardly when the blade 131 rises, and when the latter is retracted it falls and presses the end of the strip beneath the edge of blade 129 and into line with opening 27. As the shears are operated upon each reciprocation of the printing frame and since the paper is fed forward on each movement a sufficient distance to present a new printing surface to the type, it is obvious that the paper which has been printed on will be divided into separate strips each of which bears memoranda recording the receipt of a single depositor's card 3 and this memoranda will include an identification of the card made from the card itself. Guides 159 (Fig. 6) may be provided so that the length of paper between the platen and the shears will be equal to a whole number of slips such as shown in Fig. 4, and each slip severed will bear the record of a single operation of the printing devices.

I preferably provide a warning signal when either the paper 21 or ribbon 29 has been exhausted or broken. This signal is illustrated partly by diagram in Figs. 5 and 6. Referring to Fig. 6, the paper strip 21 passes between two metal cross rods 161 and 163 connected in circuit with a battery 165 and a buzzer 167. A wire bail 169 has its arms journaled on bar 163 and is normally supported free of the bar 161 by the interposed paper strip. If the paper strip gives out or breaks, the bail can swing under gravity into contact with bar 161 and the circuit to the buzzer will be closed and a warning signal given. A similar signal is provided for the inking ribbon 29 in the form of a bail 171 having its arms pivoted to bar 163 and supported out of contact with the shaft of roll 31 by the ribbon. If the ribbon is withdrawn for any reason, the bail will fall into contact with the shaft, the circuit will be closed as before, and the alarm given.

In the appended claims I have referred for purposes of distinction to the paper strip as a primary record-receiving element and to the depositor's card 3 as a secondary record-receiving element. This phraseology is significant only for purposes of distinction.

I have described in considerable detail the embodiment of my invention illustrated in the accompanying drawings, and in doing so have used specific words to refer to the various mechanical elements. I have

also spoken as if the machine were limited to a single use. While the mechanism illustrated is particularly designed and adapted for that use, of course the scope of my invention is not limited thereto, nor are all the mechanical details of the present embodiment essential.

What I do claim and desire to secure by Letters Patent is:

1. A machine of the class described having means for holding a primary record receiving element, inking means, a platen, type and a presser opposing said platen, guides for positioning a secondary record receiving element and arranged to position a portion thereof between said presser and platen, and type for marking said secondary element, said latter type being movable to permit it to mark said secondary element in desired location, said former type being concomitantly adjustable to record such location on the primary element.

2. In a machine of the class described, a printing member movable to print in different locations, one or more printing members arranged to print in fixed location, said members having a plurality of types and being shiftable to present different types for printing and connecting mechanism whereby movement of said first member causes shifting of said second member or members.

3. In a machine of the class described, means for positioning record receiving means, a frame mounted in opposition thereto for relative impressing movement, a member slidale in said frame, printing means carried thereby, one or more type wheels carried by said frame, and shafts connected to said wheels to rotate the same, said shafts being operatively related to said member to turn on sliding thereof.

4. In a machine of the class described, means for positioning record receiving means, a frame mounted in opposition thereto for relative impressing movement, a member slidale in said frame, printing means carried thereby, one or more type wheels carried by said frame, and screw shafts connected to said wheels to rotate the same,

said member embodying one or more nut-like portions coöperating with said screw shafts.

5. A machine of the class described, comprising means for holding and feeding a paper strip, impression means and a co-operating platen on opposite sides of the same, means for positioning an element of standard size, type movable for marking thereon in desired location, said positioning means being arranged to position a portion of said element between said platen and impression means, and mechanism for operating said impression means and said type.

6. A machine of the class described, comprising means for holding a primary record receiving element, a guide for a secondary record receiving element, printing means arranged to coöperate with said primary element, printing means arranged to coöperate with said secondary element, said secondary element and the corresponding printing means being relatively movable to alter the position of the record on the element, said first-mentioned printing means including type shiftable by the adjusting movement of said parts for recording on the primary element an indication of such position, and means to operate said printing means.

7. A machine of the class described, comprising a box or casing, means for holding a primary record receiving element, means for positioning a secondary record receiving element arranged to permit its insertion from the exterior of the box, type for marking said secondary element movable to mark thereon in different positions, shiftable type for marking said primary element, means including a single handle exterior to the box for moving said first-mentioned type and shifting said second-mentioned type in correlation, and means including a handle exterior to the box for printing from said types.

In testimony whereof I have signed my name to this specification.

JOHN J. DIEHL.
